UNITED STATES PATENT OFFICE.

CHARLES W. SARGENT, OF MURRAY, IDAHO.

DRILL-CHUCK.

SPECIFICATION forming part of Letters Patent No. 766,733, dated August 2, 1904.

Application filed June 8, 1903. Serial No. 160,544. (No model.)

To all whom it may concern:

Be it known that I, CHARLES W. SARGENT, a citizen of the United States, residing at Murray, in the county of Shoshone and State of Idaho, have invented a new and Improved Drill-Chuck, of which the following is a specification.

This invention relates, more definitely stated, to chucks for rock-drills; and it consists in a chuck of the character stated having new and improved means for securing the bit in the chuck-socket, which means will hereinafter be fully described, and the novel features pointed out in the subjoined claim.

While my invention is specially designed and intended for securing in the chuck-socket drills of any type, it is equally adapted to tool-handles in general, having a socket for receiving the shank end of any tool adapted thereto.

In order to enable others to make and use my invention, I will now proceed to describe it in detail with reference to the accompanying drawings, forming a part of this specification.

In the drawings, Figure 1 is a plan view illustrating my invention. Fig. 2 is a longitudinal sectional view taken on line *w w* of Fig. 1, and Fig. 3 is a transverse sectional view taken on line *y y* of Fig. 1.

In the preferred form of my invention I employ a chuck-head or body portion A, which may be understood to be an enlargement at the lower end of the exteriorly-projecting portion of the piston-rod of a steam or compressed-air rock-drill of the usual or any preferred type. The head portion A is formed with a socket B, adapted to receive a special bushing C. The head and bushing are provided with lateral slots D, adapted to receive an elongated key D'. It will be noticed that the key D' is formed with a projection D² with extended side edges D³, which overlap the lateral slot-opening D in the head A. The under side of the extended edges D³ is curved, as shown, adapting the key for rocking movement in adjusting itself to a tapering bit-shank. The outer side of the projection D² on the key D' is made concave, as at D⁴, conforming to the curved edges D³ and with the

rounding under side E of the lateral head extension E' to the securing-bolt E².

In further carrying out my invention I form on the lower end of the chuck-head A a half-round strengthening-rib A'. Suitably above the lower end of the head an enlargement A² is provided and through which an opening A³ is made adapted to receive the securing-bolt E². The upper side of the enlargement A² is made projecting, as at A⁴, (see Fig. 2,) and recessed at A⁵, (see Fig. 1,) adapted to receive and support the upper squared end portion of the securing-bolt E². It will be noticed that the upper enlargement on the chuck-head is made sufficiently projecting to protect the securing-bolt head from engagement whereby it may be knocked off or injured during operation of the drill. In connection with the bolt E² I employ a nut E³, having increased thread-bearing which is provided by the tapered and projecting under side E⁴, adapted for seating in an enlarged recess or opening E⁵ at this end of the bolt-opening through the enlargement A².

According to my invention the bushing C is recessed, as at C', adapted for engagement with the securing-bolt E² and whereby the bushing is locked in place. A similar recess C² is formed on the opposite side of the bushing C, adapting it to be reversed when in use one end becomes worn or unduly enlarged.

The above description, in connection with the several views shown in the drawings, will render my invention fully understood. I would, however, call particular attention to the form of my special key, the reversible bushing, and the peculiar clamping-bolt, as also the means employed whereby the bolt-head is afforded protection and bracing support.

Having thus described my invention, what I claim as new, and desire to secure by Letters Patent, is—

The combination in a chuck having an axial socket and a lateral slot extending into the said socket, and also a transverse opening adapted to receive a clamping-bolt, of an enlargement on the chuck-head having a lateral projection, the said enlargement and projec-

tion having an angular recess therethrough forming an extension of the said transverse opening, a bushing in the said axial socket having a lateral slot conforming with the slot 5 in the chuck-head, the bushing having opposite exterior recesses adapting it in reversed position, to receive the clamping-bolt, a key adapted to enter the lateral slots in the chuck-head and bushing, having overlapping side 10 edges with curved under sides and a top con-

caved surface, a laterally-projecting head on the clamping-bolt, having an under curved surface adapted to seat in the upper curved surface on the key, and a securing-nut on the said bolt, substantially as described.

CHARLES W. SARGENT.
